UNITED STATES PATENT OFFICE

167,325

EMBROIDERED TRIMMING OR THE LIKE

John M. Sniderman, New York, N. Y.

Application February 4, 1952, Serial No. 18,351

Term of patent 3½ years

(Cl. D92—1)

To all whom it may concern:

Be it known that I, John M. Sniderman, a citizen of the United States, residing at city of New York, in the county of New York and State of New York, have invented a new, original, and ornamental Design for an Embroidered Trimming or the like, of which the following is a specification, reference being had to the accompanying drawing, forming part thereof.

In the drawing, the figure is a plan view of a piece of embroidery trimming, showing my new design.

I claim:

The ornamental design for an embroidered trimming or the like, substantially as shown.

JOHN M. SNIDERMAN.
